UNITED STATES PATENT OFFICE.

JAMES N. OLIVER AND CAMPBELL B. OLIVER, OF GENESEE, IDAHO TERRITORY.

FOOT-BOARD FOR HEADING-MACHINES.

SPECIFICATION forming part of Letters Patent No. 417,331, dated December 17, 1889.

Application filed May 31, 1889. Serial No. 312,713. (No model.)

To all whom it may concern:

Be it known that we JAMES N. OLIVER and CAMPBELL B. OLIVER, citizens of the United States, residing at Genesee, in the county of 5 Latah and Territory of Idaho, have invented certain new and useful Improvements in the Foot-Boards of Heading-Machines; and we do declare the following to be a full, clear, and exact description of the invention, such as 10 will enable others skilled in the art to which it appertains to make and use the same, reference being had to the accompanying drawings, and to the letters of reference marked thereon, which form a part of this specification. 15

The special object of the invention is to make an improvement in the foot-boards of header-harvesters, so that the driver may adjust the same with his foot, as hereinafter described. 20

Figure 1 of the drawings is a plan view of the foot-board, its attachments, and the beam or bar to which they are fastened. Fig. 2 is 25 a side elevation, and Fig. 3 a vertical section on the dotted line $x x$ of Fig. 1.

In the drawings, A is the foot-board of a harvester pivoted on the bearings B and supported by an arc bar C in the slot d of a bracket D, the parts B D being securely 30 bolted or otherwise fastened to the bar E. In the uprights $d' d'$ is loosely arranged a pin or bolt F, which passes through the bearings d^2 d^3 and into one of the arc-bar holes c, so as to hold the foot-board. The bolt F is un-

locked from the bar by means of its auxiliary 35 plate F', which has on the inner end and at right angles thereto the flat head f, against which the heel of the driver's foot is pressed to shoot the bolt back. As soon as the back-pressure of his foot is removed the spiral 40 spring G, located between the bolt-bearing d^2 and the plate-head f, shoots the bolt into one of the arc-plate holes c.

In using the harvester the driver stands on the foot-board A and has his hands employed 45 so that on hillsides there is great difficulty in preventing his feet from slipping on the inclined foot-board. This, however, is entirely prevented by our adjustable foot-board, which is easily operated by a backward move- 50 ment of one of his feet.

What we claim as new, and desire to protect by Letters Patent, is—

The combination, in a heading-machine, of the pivoted foot-board A, bearing B, arc bar 55 C, having holes c, bracket D, having the uprights $d' d'$ and bearings $d^2 d^3$, the loose bolt F, the auxiliary plate F', having the flat head f, and the spiral spring G, all arranged substantially as shown and described. 60

In testimony whereof we affix our signatures in presence of two witnesses.

JAMES N. OLIVER.
CAMPBELL B. OLIVER.
